(57) **CLAIM**

The ornamental design for a plunger rod and finger grip for a syringe, as shown and described.

DESCRIPTION

FIG. 1 is a front perspective view of a plunger rod and finger grip for a syringe according to my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded front perspective view thereof;

FIG. 9 is an enlarged view of portion "9" shown in FIG. 2; and,

FIG. 10 is an enlarged view of portion "10" shown in FIG. 2.

The broken lines shown represent portions of the plunger rod and finger grip for a syringe that form no part of the claimed design.

1 Claim, 4 Drawing Sheets
